(57) **CLAIM**

The ornamental design for a soft roller wheel system, as shown and described.

DESCRIPTION

FIG. 1 is a perspective view from the upper corner of the soft roller wheel system attached to a luggage case. The luggage case, shown in broken lines, is merely environmental and does not form any part of the claimed design.

FIG. 2 is a perspective view of the soft roller wheel system.

FIG. 3 is a side view thereof.

FIG. 4 is a front view thereof.

FIG. 5 is a bottom view thereof.

FIG. 6 is a side view, viewed from the side other than that shown in FIG. 3; and,

FIG. 7 is back perspective view thereof.

1 Claim, 4 Drawing Sheets

FIG. 1

FIG. 2

FIG. 3

FIG. 4

FIG. 5

FIG. 6

FIG. 7
